US00D757043S

(12) **United States Design Patent**
Zankowski et al.

(10) **Patent No.:** US D757,043 S
(45) **Date of Patent:** ** May 24, 2016

(54) **DISPLAY SCREEN WITH GRAPHICAL USER INTERFACE**

(71) Applicant: **Comcast Cable Communications, LLC**, Philadelphia, PA (US)

(72) Inventors: **Jack Zankowski**, Haddonfield, NJ (US); **Heather Hollis**, Ardmore, PA (US); **Thomas Loretan**, Trumbull, CT (US)

(73) Assignee: **Comcast Cable Communications, LLC**, Philadelphia, PA (US)

(**) Term: **14 Years**

(21) Appl. No.: **29/492,224**

(22) Filed: **May 29, 2014**

(51) LOC (10) Cl. **14-04**

(52) U.S. Cl.

USPC **D14/485**

(58) **Field of Classification Search**

USPC D14/485-488, 489-495; D20/11, 22, D20/27

CPC G06T 2200/24; G06F 3/0489; G06F 15/0225; G06F 17/30115; H04N 21/482; H04N 5/44543; H04N 21/478; H04H 60/72

(57) **CLAIM**

The ornamental design for a display screen with graphical user interface, as shown and described.

DESCRIPTION

The FIGURE is a front view of a display screen with graphical user interface showing our new design.

The broken line showing of the remainder of the user interface and the remainder of the display screen is for environmental purposes only and forms no part of the claimed design.

1 Claim, 1 Drawing Sheet
